GRILLEWORK FOR TREILLAGES, ROOM DIVIDERS OR THE LIKE

Ron Furtak, Chicago, Ill., assignor to Julius Blum & Co., Inc., Carlstadt, N.Y., a corporation of New York

Filed Apr. 21, 1969, Ser. No. 16,823

Term of patent 14 years

Int. Cl. D25—01

U.S. Cl. D54—2

FIG. 2

FIG. 1

FIG. 3

FIG. 4

FIG. 1 is a front elevational view of a grillwork for trellages, room dividers or the like;

FIG. 2 is an end elevational view thereof taken along line 2—2 of FIG. 1;

FIG. 3 is a view similar to FIG. 2, taken along line 3—3 of FIG. 1;

FIG. 4 is a bottom elevational view;

FIG. 5 is a sectional view taken along line 5—5 of FIG. 1;

FIG. 6 is a sectional view taken along line 6—6 of FIG. 1;

FIG. 7 is a sectional view taken along line 7—7 of FIG. 1; and

FIG. 8 is a sectional view taken along line 8—8 of FIG. 1.

I claim:

The ornamental design for grillwork for trellages, room dividers or the like, substantially as shown and described.
